UNITED STATES PATENT OFFICE.

JAMES L. MURPHY, OF CHICAGO, ILLINOIS.

COLLAR.

1,388,661.

Specification of Letters Patent. Patented Aug. 23, 1921.

Application filed July 31, 1920. Serial No. 400,414.

To all whom it may concern:

Be it known that I, JAMES L. MURPHY, a citizen of the United States, residing at Chicago, in the county of Cook and State 5 of Illinois, have invented certain new and useful Improvements in Collars, of which the following is a description.

My invention belongs to that general class of articles known as collars, and particularly 10 that type termed soft or semi-soft or negligée collars. It refers more particularly to collars which are not stiffly starched, and in which it is desirable to arrange to support and secure the meeting ends. In such 15 collars it has been customary to sew a button upon the outermost face of the neck-band at a suitable point, and to button the projecting or overlying flap of the opposite end of the collar thereto, in addition to buttoning the collar both in the rear and front to the neck-band of the shirt. This method is 20 objectionable by reason of the fact that the button thus attached is in the way in laundering the collar, and is very often broken. 25 With this type of collar there is also the tendency for the same to wrinkle or bend down and trouble is often caused by the collar shrinking in laundering. The invention has among its objects the production of a 30 collar of the kind described that is simple, convenient, comfortable, attractive, durable, and satisfactory under all conditions. Many other objects and advantages of the construction herein shown and described will 35 be obvious to those skilled in the art from the disclosures herein made.

To this end my invention consists in the novel construction, arrangement and combination of parts herein shown and described, 40 and more particularly pointed out in the claims.

In the drawings, wherein like reference characters indicate like or corresponding parts,

45 Figure 1 is a perspective view of a collar illustrating my improvements applied thereto;

Fig. 2 is a face view of one end of the collar with the outer part bent upward from 50 the neck-band to more clearly show the construction;

Fig. 3 is a similar view of the opposite end;

Fig. 4 is a sectional view taken substantially on line 4—4 of Fig. 2;

Fig. 5 is a sectional view taken substantially on line 5—5 of Fig. 2;

Fig. 6 is a perspective view of a portion of a stay;

Fig. 7 is a perspective view of a modified 60 form of stay;

Fig. 8 is a sectional view of another modified form of stay; and

Fig. 9 is a sectional view taken substantially on line 9—9 of Fig. 8.

In the drawings, 1 represents the neck-band of the collar, and that portion coming in contact with the neck may be termed the "inner face," and that portion which is outermost from the neck may be termed the 70 "outermost face." There is also provided at the upper edge 3 a down-turned outer fold 2 of the desired shape and size. Obviously the collar may be made of any suitable material and of the desired shape or design, as 75 well as size.

The neck-band is ordinarily composed of a plurality of plies of material laid one upon the other and stitched or sewed together to give body to the same. I have 80 shown the band provided with the usual button hole 4 at the back and with button holes at the extreme ends. In the type of collar shown, the extreme ends 5 and 7 are arranged to overlie in the usual manner and 85 be secured to the neck-band at the front of the shirt by a suitable button. I have shown button holes 6 and 8 in the ends for engaging with the button, and in this connection it may be mentioned that I prefer to make the 90 button holes substantially with two holes or openings in alignment 6 and 6' and 8 and 8', that is, in pairs or in duplicate, so that when the collar shrinks the outer holes may be used if necessary. That is to say, when the 95 collar is first used, the holes 6' and 8' may be used, but after the same has been laundered and has shrunk, the holes 6 and 8 may be employed.

I also preferably provide a similar double 100 button hole 9 and 9' at the top so that the end 7 may be secured to the opposite end of the collar, as will be hereinafter described. In the preferred collar, I provide stays 14 and 15 of suitable material, for example 105 celluloid or pyrolin, it being understood, however, that any material suitable for the purpose may be used, and that the same may be covered if preferred. These stays may be secured to the collar in any desired man- 110

ner, preferably so that they may be detached when the collar is laundered, and for the purpose I have shown pockets 10 and 12, which are suitably stitched or sewed, as at 5 11 or 13, or any equivalent manner to the collar. These are made of a size and shape to receive the stays, which are preferably made of a length substantially equal to the width of the band, and they are arranged on 10 the outermost face so that the stays are positioned between the band and portion 2 of the collar.

I prefer to provide on one of the stays, as shown stay 14, means for detachably engaging with the end 7 of the band. The engaging means may be in the form of a projecting part, knob or button, which will coöperate with the button hole 9 or 9' and secure the end of the collar. In Figs. 2, 4 and 6, 15 20 I have shown the stay constructed of celluloid with the portion 16 struck out so as to form a hook or engaging member which will engage in the button holes 9 or 9'. In Fig. 7 the stay 14' is punched out or formed with 25 a knob or button 16', which in this case is formed integral with the stay similar to the projecting part 16. In Fig. 8 I have shown a stay 19 of suitable material, which may be covered as at 20 if desired, and to which is 30 sewed or otherwise secured a button 21, as indicated at 22. Obviously any of the stays will operate in the same manner and engage in the button holes so as to retain the upper edge of the collar.

35 In use the stays are positioned and the collar applied to the neck band of the shirt in the usual manner, the end 7 may be buttoned or hooked on to the stay 14, thereby locking it firmly in place. When it is desired to laundry the collar, the stays may be removed, and in this connection, it will be particularly noted that there are no buttons to be broken, nor fasteners to rust. When the stay is repositioned, the engaging 40 45 member is at the same time positioned ready for use.

Having thus described my invention, it is obvious that various modifications may be made in the same without departing from the spirit of my invention; hence I do not wish to be understood as limiting myself to the exact form, construction, arrangement and combination of parts herein shown and described, or uses mentioned.

50 55 What I claim as new and desire to secure by Letters Patent is:

1. In a collar of the kind described and in combination, a neck-band having the two ends of the same constructed to overlie, and 60 provided with buttonholes for engaging the buttons carried by a shirt-band, and a stay detachably carried by said neck-band adjacent one end to one side of the buttonhole at said end and provided with engaging means, 65 the opposite end of the neck-band provided

with means for coöperating with said engaging means.

2. In a collar of the kind described and in combination, a neck-band having the two ends of the same constructed to overlie, and 70 provided with duplicate buttonholes for engaging a button carried by a shirt-band, a stay detachably carried by said neck-band to one side of the buttonholes adjacent one end and provided with engaging means, the opposite end of the neck-band provided with means for coöperating with said engaging means.

3. In a collar of the kind described and in combination, a neck-band having the two 80 ends of the same constructed to overlie, and provided with means for attaching the same to a shirt-band, stays arranged one adjacent each end of the neck-band and detachably secured thereto, one of said stays provided 85 with engaging means, the neck-band at the opposite end provided with a hole for coöperating with said engaging means and detachably securing the two ends of the collar together thereat.

90 95 100 4. In a collar of the kind described and in combination, a neck-band having the two ends of the same constructed to overlie, and provided with means for attaching the same to a shirt-band, stays arranged one adjacent each end of the neck-band and detachably secured thereto, one of said stays provided with integrally formed engaging means, the neck-band at the opposite end provided with means coöperating with said 105 engaging means for detachably securing the two ends of the collar together thereat.

110 115 120 5. In a collar of the kind described and in combination, a neck-band having the two ends of the neck-band constructed to overlie, and provided with means for attaching the same to a shirt-band, said neck-band provided with an overlying exterior part, stays arranged one adjacent each end of the said neck-band between the band and the overlying portion, means for detachably securing said stays to said neck-band, and means carried by one stay for engaging the opposite end of the neck-band and securing the same thereto.

125 130 135 6. In a collar of the kind described and in combination, a neck-band having the two ends of the neck-band constructed to overlie, and provided with buttonholes in pairs for attaching the same to the front button carried by a shirt-band, said neck-band provided with a folded over exterior portion, stays arranged one adjacent each end of the said neck band between the band and the folded over portion, means for detachably securing said stays to the collar, and means carried by one stay for detachably engaging the opposite end of the neck-band and securing the same thereto.

7. In a collar of the kind described and in

combination, a neck-band having the two ends of the same constructed to overlie, and provided with buttonholes in pairs for attaching the same to a shirt-band, the holes 5 of said pairs lying in a single line, a stay detachably carried by said band adjacent one end and provided with engaging means, the opposite end of the band provided with means for coöperating with said engaging 10 means.

8. In a collar of the kind described and in combination, a neck band having the two ends of the same constructed to overlie, and provided with buttonholes for engaging the 15 buttons carried by a shirt-band, a pocket

carried by said neck-band adjacent one end, and extending transversely thereof, and a stay detachably carried in said pocket to one side of the buttonhole at said end and provided with engaging means, the opposite end 20 of the neck-band provided with means for coöperating with said engaging means.

In testimony whereof, I have hereunto signed my name in the presence of two subscribing witnesses.

JAMES L. MURPHY.
